UNITED STATES PATENT OFFICE.

MAUDE M. LLOYD, OF NEW YORK, N. Y.

ADJUSTABLE HAT.

Application filed July 6, 1921. Serial No. 482,860.

The invention has for an object to provide a hat which will fit securely on the head of the wearer, and which will be adjustable to the end that the same hat may be made to fit equally well over any desired range of sizes.

Another object of the invention, as applied to women's hats, is to combine the features above mentioned with other features rendering the hat particularly advantageous for outing or "sport" purposes, and yet to construct the hat in such manner that it readily may be adjusted into a form suitable for ordinary wear, without being made unsightly or of inappropriate shape, by the aforesaid features.

Further objects and advantages of the invention will be in part obvious and in part specifically pointed out in the description hereinafter contained, which taken in connection with the accompanying drawings, discloses a preferred embodiment of the invention; such embodiment, however, is to be considered merely as illustrative of its principle. In the drawings:

Fig. 1 is a front view of a woman's hat embodying the features of the invention, the brim, or vizor, of the same being adjusted to a lower position to shade the eyes of the wearer;

Fig. 2 is a view similar to Fig. 1 but with the brim, or vizor, turned upwardly to form a hat of the coronet type;

Fig. 3 is a bottom view of the hat;

Fig. 4 is a section on line 4—4 of Fig. 3 looking in the direction of the arrows;

Fig. 5 is a section on line 5—5 of Fig. 1 looking in the direction of the arrows.

Referring to the drawings I have disclosed a hat having a head size band 1, which, however, is not in the form of an endless band as is usual, but is formed with two ends 2 and 3 which are movable relative to each other so that the effective periphery of the band may be adjusted by holding said ends in position at varying distances from each other, whereby the hat may be adjusted to different sizes or fitted securely upon the head of the wearer.

In order to hold the ends 2 and 3 of the head size band 1 in any desired position relative to each other I employ securing members 4 and 5 which are attached respectively to the ends 2 and 3 of the band 1 and thus by fixing these members in position, when the ends 2 and 3 are spaced from each other

the desired distance, the size of the hat will remain as desired. I prefer to make the securing members 4 and 5 in the form of strips which cross each other adjacent the ends 2 and 3 of the head size band and extend around the exterior of the latter to form a side band for the hat as well as to bear against the head size band and assist in holding the hat in proper position. As shown, the ends 2 and 3 of the head size band are located at the rear of the hat and the securing strips 4 and 5 extend around the opposite sides of the same until their ends meet at the front where they are suitably fastened together, as by a ball and socket fastening 6.

Thus the hat may be placed upon the head of the wearer with the ends of the strips 4 and 5 free and such strips may then be pulled until the desired tightness of fit is obtained, after which the ends of the strips are fastened together at the front of the hat to hold it in adjusted position. The hat, therefore, may be adjusted to a very tight fit, for example, as would be desired for automobile or sporting wear, while if the hat is to be worn for ordinary purposes the fit may be made less tight. Furthermore, the adjustability and size of the hat may be made sufficient to enable the one hat to serve equally well over any desired range in sizes.

The frictional engagement between the strips 4 and 5 and the outer side of the head size band, as well as the fastener 6, will tend to keep the hat adjusted to the desired size once the adjustment has been made, but I prefer, also, to provide one or both of said strips with an elastic portion 7 which exerts sufficient tension to take up any loosening allowed by the strips 4 and 5 and yet does not cause sufficient pressure to render the hat uncomfortably tight as might be the case if an elastic band, or the like, were relied upon to bring about a tight fit. The elastic portion 7 also enables the single fastener 6 to be used since in fitting the hat the wearer merely pulls the strips 4 and 5 until the desired fit is obtained, and then fastens together the ends of the strips by the fastener 6, the elastic portion 7 allowing enough expansion or contraction to obviate the necessity of securing together different parts of the strips 4 and 5 in different size adjustments.

The crown 8 of the hat is secured to the head size band 1 and should be made of

material sufficiently flexible to permit any adjustment in size, as above described. I prefer to leave the lower edge 9, for instance, Fig. 4, of the crown free of the head size band so that the ends 2 and 3 may be readily shifted and without unduly distorting the shape of the hat. The periphery of the lower edge of the crown 8 I also prefer to make at least equal to the maximum 10 adjustment of the head size band and thus the material of the crown will not be unduly strained in making the adjustments and the effect of adjusting the hat to the smaller sizes will merely be to create a 15 slight pucker at the rear of the crown.

As shown, particularly in Fig. 4, the crossing of the strips 4 and 5 may be effected neatly by providing a slit 10 in the strip 4 and tapering the strip 3 to enable the same 20 to be inserted through such slit and passed around the side of the band 1. As previously described it will be understood that the strips 4 and 5 may be integral with the band 1, if desired, or in the form of separate 25 pieces attached thereto.

The brim 11 may be secured to the band 1 in any suitable manner and in order that the brim shall not interfere with the size adjustability of the hat, it preferably does not 30 extend completely around the same but is provided with independent ends 12 and 13 respectively secured to the ends 2 and 3 of the head size band or the adjacent portions of the strips 4 and 5, and thus the ends 12 and 35 13 of the brim follow the movements of the ends 2 and 3 and meet, or overlap to some extent, in all adjustments of the hat with the result that the appearance of the rear of the brim is uniform for all conditions.

40 The structure of the hat, whereby it may be firmly fitted, is particularly useful for outing or sporting wear, but preferably, the hat as a whole is so constructed that it, nevertheless, will be suitable for ordinary wear. 45 A vizor-like portion 14 provided at the front of the brim 11 may be turned down, as indicated in Fig. 1, to shade the eyes of the wearer. When the hat is adjusted in this manner it is appropriate for outing purposes but does not have the form of a dress-hat. However, the vizor 14 may be turned 50 upwardly, as indicated in Fig. 2, to cover at least, partially, the strips 4 and 5, thus changing the appearance of the hat to that of a dressy coronet model. The features of the hat which are specially useful in connection with outing wear, therefore, do not render the same unsuitable for ordinary purposes since the adjustment of the vizor 14, 55 as above described, is all that is necessary to transform the hat from one above mentioned type to the other, making the hat useful for both occasions.

60 While a specific embodiment of the invention has been described it is obvious that

many changes may be made therein without departing from its principle as defined in the following claims.

I claim:

1. An adjustable hat comprising a single 70 piece head size band having ends, a crown attached to said band, the ends of said band being movable toward and away from each other to adjust the effective periphery of the band, securing members respectively attached to the ends of said band and adapted to be detachably fastened to hold the ends of the band in position at different distances from each other, said securing members comprising strips crossing each other adjacent the ends of the head size band and extending around the exterior of the latter to form a side band for the hat.

2. An adjustable hat comprising a single 85 piece head size band having ends, a crown attached to said band, the ends of said band being movable toward and away from each other to adjust the periphery of the band, securing members respectively attached to the ends of said band and crossing each 90 other adjacent the ends of said band and extending around the exterior of the latter to form a side band for the hat, the free ends of said securing members being detachably fastened together.

3. An adjustable hat comprising a single 100 piece head size band having ends, a crown attached to said band, the ends of said band being movable toward and away from each other to adjust the effective periphery of the band, securing members respectively attached to the ends of said band and adapted to be detachably fastened to hold the ends of the band in position at different distances from each other, one or both of said securing members having an elastic portion therein.

4. An adjustable hat, comprising a single 110 piece head size band, a crown attached to said band, said band having ends relatively movable to adjust the effective periphery of the band, and means attached to one of said ends adjustable to hold the same in position at varying distances from the remaining end of the band, said means comprising a strip secured to said adjustable end of the band 115 and overlying the exterior of the head size band to form a side band for the hat.

5. An adjustable hat comprising a head 120 size band, a crown attached thereto, the ends of said band being movable toward and away from each other to adjust the effective periphery of the band, securing members respectively attached to the ends of said band and extending around the exterior of the latter in opposite directions to form a side band for the hat, one of said members having a slit adjacent the ends of the head size band through which slit the remaining securing member passes.

6. An adjustable hat comprising a single 130

piece head size band having ends, a crown attached to said band, the ends of said band being movable toward and away from each other to adjust the effective periphery of the band, securing members respectively attached to the ends of said band and adapted to be detachably fastened to hold the ends of the band in position at different distances from each other, said securing members comprising strips crossing each other adjacent the ends of the head size band and extending around the exterior of the latter to form a side band for the hat, and a brim for the hat secured to the head size band and having independent ends respectively secured to the ends of the head size band.

7. An adjustable hat, comprising a single piece head size band having ends, a crown attached to said band, the ends of said band being movable toward and away from each other to adjust the effective periphery of the band, securing members respectively attached to the ends of said band and adapted to be detachably fastened to hold the ends of the band in position at different distances from each other, said securing members comprising strips crossing each other adjacent the ends of the head size band and extending around the exterior of the latter to form a side band for the hat, and a brim for the hat secured to the head size band and having independent ends respectively secured to the ends of the head size band, the ends of the head size band being disposed at the rear of the hat, and said brim having a vizor-like portion at the front adapted to be turned up to at least partially cover the side band.

8. An adjustable hat, comprising a single

piece head size band, a crown attached thereto, said band having ends relatively movable to adjust the effective periphery of the band, and means attached to one of said ends adjustable to hold the same in position at varying distances from the remaining end of the band, the crown being free of the head size band adjacent its movable end, and a brim for the hat secured to the head size band and having independent ends respectively secured to the ends of the head size band.

9. An adjustable hat comprising a single piece head size band having ends movable toward and away from each other to adjust the effective periphery of the band, a crown attached to said band, a securing member attached to each of the ends of said band and frictionally engaging the exterior of the band in various positions to hold the hat in adjusted position.

10. An adjustable hat comprising a single piece head size band, a crown attached thereto, the ends of said band being movable toward and away from each other to adjust the effective periphery of the band, securing members respectively attached to the ends of said band extending around the exterior of the latter in opposite directions to frictionally engage said band and to form a side band for the hat and an elastic member attached to each securing member and adapted to fasten to hold said securing members in said frictional engagement thereby to retain the hat in adjusted position.

In testimony that I claim the foregoing, I have hereunto set my hand this 30 day of June, 1921.

MAUDE M. LLOYD.
